UNITED STATES PATENT OFFICE.

FREDERICK A. PRESTON, OF HIGHLAND PARK, ILLINOIS, ASSIGNOR TO THE P. & M. CO., OF CHICAGO, ILLINOIS, A CORPORATION OF ILLINOIS.

ANTICREEPER.

1,152,760.

Specification of Letters Patent.

Patented Sept. 7, 1915.

Application filed October 23, 1914. Serial No. 868,234.

To all whom it may concern:

Be it known that I, FREDERICK A. PRESTON, a citizen of the United States, residing at Highland Park, in the county of Lake 5 and State of Illinois, have invented new and useful Improvements in Anticreepers, of which the following is a full, clear, concise, and exact description, reference being had to the accompanying drawing, forming a 10 part of this specification.

My invention relates to improvements in rail anchors or rail stays, such devices being used to prevent the longitudinal creeping of railway rails.

15 The present invention is applicable more particularly to rail anchors of the general character indicated in my prior Patent 1,101,658, June 30th, 1914, said prior rail anchor consisting essentially of a yoke and 20 a coöperating tongue, said tongue being held in flexed position by said yoke whereby continual pressure is exerted on said yoke to maintain it in effective gripping position on the rail base at all times.

25 The present improvement is directed more particularly toward providing a more positive wedging engagement between the yoke and the tongue, that is, one less dependent for its efficiency on the resiliency of the 30 tongue or wedge, and the object of the invention is to provide an improved anti-creeper having the desirable characteristics just mentioned.

In the accompanying drawings, I have 35 illustrated several embodiments of the invention, which latter is, of course, susceptible of further embodiments.

Figure 1 is a rear elevation of one form 40 of rail anchor, the rail being shown in section. Fig. 2 is a side elevation thereof. Fig. 3 is a fragmentary elevation of a further form of device. Fig. 4 is a section on the line 4-4 of Fig. 3. Fig. 5 is a fragmentary elevation of a further form of device showing one step in the assembly thereof. Fig. 6 is a corresponding elevation of 45 the final position of the parts. Fig. 7 is a side elevation of an additional form of rail anchor.

50 In the various views, the rail is indicated by reference character 1 and the usual cross-tie by reference character 2.

In Figs. 1 and 2, the rail anchor comprises a suitable yoke 3, preferably a forging, although it may be made of malleable

iron or other suitable material, and a wedging member or tongue 4. The latter is made preferably of malleable iron, although it may be made of any suitable material which may be bent slightly without breaking. The 60 yoke 3 is arranged so that its upwardly curved ends bear against the top of the rail base near the outer edges thereof, one of said ends being slightly offset adjacent to the shoulder 5 to aid in positioning the yoke 65 on the rail base. The wedging member 4 is provided with a downwardly extending end 6 constituting a tie abutting flange. Said member tapers from the front end toward the middle, forming in effect, a rearwardly 70 pointing wedge 7. The rear part 8 of said member is arranged normally to lie close to and nearly parallel to the base of the rail as indicated by dotted lines in Fig. 2. After the yoke and the wedge have been assembled 75 on the rail base, however, suitable means are employed for bending or springing down the rear end of said wedge member so as to provide a double wedge as shown in Fig. 2, the rear wedge pointing forwardly and the 80 forward wedge as previously stated, pointing rearwardly. The yoke 3 is located at the small end of both wedges whereby it is prevented from moving either forward or backward along the rail base, and whereby any tendency toward forward or backward 85 movement results in increasing the grip of the rail anchor, as a whole, on the rail base. The rear end 8 of the wedging member may be forced downwardly in various ways. In 90 Figs. 1 and 2, I have shown a wedge 9 made preferably of either malleable iron or as a forging, and somewhat longer than the width of the rail base, which wedge may be driven forward by hammer blows directed against the two projecting ends thereof, said wedge serving not only to force downwardly the rear part 8, but serving also as a filler block whereby a solid backing for the rear extension 8 is provided. This insures practically a solid wedge for the yoke 3 in the same sense that the forward part 7 constitutes a solid wedge, so that the yoke maintains a continual pressure on the rail independently, in the main, of any resiliency of the wedging member as a whole. The wedge 8 is locked against a rearward movement by a beveled catch or shoulder 10 at the extreme rear of the wedging member.

It will be seen that when the rail tends to 110

creep, the yoke 3 will tend to ride along the forward wedge 7, thus increasing its grip on the rail base and arresting said creeping, the forward thrust being transmitted to the tie through the flange 6. If the rail should retract, relieving the pressure of the flange 6 against the tie, the firm grip of the anchor on the rail base will be maintained regardless of the absence of a thrust tending to force the wedge 7 into the yoke. If the ballast should be tightly packed in the rear of the flange 6, or be frozen solid in winter, so as to obstruct the rearward movement of said flange with the rail, the yoke 3 will then tend to ride along the rear wedge 8. This tendency also, as in the first case described, results in a further tightening of the hold of the rail anchor on the rail base, the rearward movement of the rail being checked to whatever extent the ballast resists the rearward pressure of said flange. It will thus be seen that a thrust of the wedging member as a whole, in either direction, that is backward or forward, can result only in a further tendency to tighten the rail anchor on the rail base. The anchor therefore, never works loose and is always effective in resisting forward creeping whenever it engages the cross-tie.

In Figs. 3 and 4, I have shown a modified form of wedge 11, which may be driven sidewise under the rail instead of being driven longitudinally with respect thereto. Said wedge is received within the curved rear end 12 of the wedging member and performs the general functions of the previously described wedge.

A further alternative construction is shown in Figs. 5 and 6 wherein a cam-like bar 13 is provided, extending transversely beneath the rail base between the latter and the rear extension 14 of the wedge member. Said bar is applied in the position shown in Fig. 5 and then turned by means of a suitable wrench to the position shown in Fig. 6, resulting in bending or springing said wedge member for the purpose described.

In Fig. 7 I have shown a further form of rail anchor in which the wedging member or tongue 15 is of resilient metal, preferably a forging of tempered steel. The yoke 16 may also be a tempered steel forging, although not necessarily so as the wedging member 15 is relied on to furnish the necessary resiliency to insure a continual pressure of the yoke on the rail base. The rear end of said wedging member is sprung downwardly in a manner quite similar to that employed with the substantially non-resilient wedging member in the form of rail anchor previously described. Any suitable means may be employed to force said rear end downwardly. I have illustrated a wedge 17 similar to the wedge shown in Fig. 2 although it is to be understood that I con-

template using any of the devices illustrated in the preceding figures. It will be seen that the wedging action between the yoke and the wedging member is quite similar in this form of rail anchor to that previously described, the yoke increasing its grip on the rail base on a tendency toward a movement either forward or backward. Instead of a solid backing for the wedging member, however, there is a clearance between said member and the rail base. Throughout most of the length thereof, the resiliency of said member, and to a slight extent, the resiliency of the yoke is relied on to maintain the pressure on the rail base whereas in the preceding forms of device, substantially solid backing is provided regardless of whether or not the wedging member has any inherent resiliency.

Having thus described my invention, what I claim as new and desire to secure by Letters Patent of the United States is:

1. A rail anchor comprising a yoke and a wedging member having double wedging surfaces extending forward and backward from the point of contact with said yoke, one of said wedging surfaces being maintained by means forced between said wedging member and the rail base after said member and yoke have been positioned on the rail.

2. The combination with means for engaging opposite sides of a rail base, of means coöperating therewith and engaging a tie, and additional means for insuring permanent coöperation between said first and second means, to grip the rail base firmly.

3. In combination, a transverse member for engaging opposite flanges of a rail base, a longitudinal member engaging a tie and a third member insuring coöperation between said first two members to enable them to resist creeping.

4. A rail anchor comprising a tie abutting member and a yoke extending around the rail base and member, which in operative position is put under stress by said member, the latter being adjustable to operative position by a movement away from the rail base.

5. A rail anchor comprising a tie-abutting member bearing against the rail base at one end, a yoke extending around said rail base and member at an intermediate part of the latter, and means for forcing the other end of said member away from the rail base to prevent movement of said yoke toward that end.

6. A rail anchor comprising a longitudinal member beneath the rail base, a transverse member embracing the sides of the rail base and bearing against the highest point of the under surface of said longitudinal member, and a third member arranged between said latter member and the rail base.

7. A rail anchor comprising a longitudinal member beneath the rail base the forward part of which has a wedging surface inclining downwardly, a yoke embracing the rail base and arranged to contact with the small end of the wedge, the rear part of said member normally lying sufficiently close to the rail base to permit said yoke to slip over it and a third member forcing the rear end of said longitudinal member away from the rail base to form a second wedge thereof, extending rearwardly from said yoke.
8. A rail anchor comprising a tie-abutting longitudinal element, a transverse rail base flange engaging element and a wedge holding the rear end of said longitudinal element away from the rail base.
9. A rail anchor comprising a tie-abutting tongue, a transverse yoke, a wedge holding the rear end of said tongue away from the rail base and means for locking said wedge in place.
10. A rail anchor comprising a yoke, a tongue arranged between said yoke and rail base and bearing at its forward end against the tie, a beveled catch at the rear end of said tongue and a wedge secured by said catch between said rear end and said rail base.
11. A rail anchor comprising a transverse rail gripping element, a longitudinal element between the latter and the rail base, said longitudinal element having a tie-abutting surface at its forward end and tapering rearwardly to said transverse element, the portion of said longitudinal element to the rear of said transverse element being held away from the rail base by an additional member to provide a forwardly tapering wedge.

In witness whereof, I have hereunto subscribed my name in the presence of two witnesses.

FREDERICK A. PRESTON.
